UNITED STATES PATENT OFFICE.

JARED MARIS, OF COLUMBUS, OHIO.

DESIGN FOR THE ORNAMENTATION OF WHEEL-HUBS.

SPECIFICATION forming part of Design No. 16,296, dated September 29, 1885.

Application filed June 23, 1885. Term of patent 3½ years.

To all whom it may concern:

Be it known that I, JARED MARIS, a citizen of the United States, residing at Columbus, in the county of Franklin and State of Ohio, have produced and invented a new and original Design, 5 of which the following is a specification, reference being had to the accompanying drawings, forming part thereof.

My invention relates to a design for the ornamentation of wheel-hubs; and it consists in a series of reverse curves on one or both flanges of the hub, the said curves giving to the periphery of the flange a wavy or corrugated appearance.

15 In the accompanying drawings, Figure 1 is a view in side elevation showing the reverse curves A. A' on one flange of the hub. Fig. 2 is a plan view showing one flange with the curves and the other flange plain, and Fig. 3 20 is a similar view showing both flanges with the wavy or corrugated periphery.

The reverse curves on one or both flanges

may be varied in size, and hence I do not restrict myself to the particular size shown and described.

Having fully described my design, what I claim as new, and desire to secure by Letters Patent, is—

1. In a design for a wheel-hub, the ornamentation of the same, consisting in a series 30 of reverse curves on the periphery of one flange of the hub, presenting a wavy or corrugated appearance, as shown and described.

2. In a design for a wheel-hub, the ornamentation of the same, consisting in a series 35 of reverse curves on the peripheries of both flanges of the hub, as shown and described.

JARED MARIS.
